CLAIM

The ornamental design for an espresso maker with accents, as shown and described.

DESCRIPTION

FIG. 1 is a top left front perspective view of a espresso maker with accents

FIG. 2 is a left side elevation view thereof;

FIG. 3 is a front view thereof;

FIG. 4 is a right side elevation view thereof;

FIG. 5 is a rear view thereof; and,

FIG. 6 is a top plan view thereof.

The broken line showing portions of the espresso maker is included for the purpose of illustrating environmental structure and forms no part of the claimed design.
